APPARATUS FOR CONTROLLING RAILWAY SWITCHES

John W. Logan, Jr., Forest Hills, Pa., assignor to
The Union Switch & Signal Company, Swiss-
vale, Pa., a corporation of Pennsylvania

Application June 4, 1938, Serial No. 211,722

2 Claims. (Cl. 246—219)

My invention relates to apparatus for controlling railway switches, and particularly to apparatus for controlling a switch from a remote point. An object of my invention is the provision of novel and improved means for controlling a power operated switch from a remote point with simple equipment and a minimum number of control wires between such point and the switch. Other objects and advantages of my invention will appear as the specification progresses.

I shall describe two forms of apparatus embodying my invention, and shall then point out the novel features thereof in claims.

In the accompanying drawing, Fig. 1 is a diagrammatic view showing one form of apparatus embodying my invention. Fig. 2 is a diagrammatic view showing a modified form of the apparatus shown in Fig. 1 and also embodying my invention.

Similar reference characters refer to similar parts in each of the two views.

Referring first to Fig. 1, the reference character S designates a railway switch of the usual and well-known form. Switch S is operatively connected with a switch mechanism SM which may, for example, be of the electropneumatic type. Switch mechanism SM, as here shown, is provided with a normal valve magnet NV and a reverse valve magnet RV, it being understood that switch S is moved by the mechanism to a normal position when valve magnet NV is energized, and to a reverse position when valve magnet RV is energized.

A circuit controller J is operatively connected with the mechanism SM and with the switch S in the usual manner. The circuit controller J comprises six movable contact fingers 1, 2, 3, 4, 5 and 6 which cooperate respectively with fixed contact fingers 1a or 1b, 2a or 2b, 3a, 4a, 5a or 5b, and 6a or 6b. It should be pointed out that circuit controller J is operated to a normal position, that is, the position illustrated in the drawing, when switch S is in its normal position, is operated to a reverse position when the switch is in its reverse position, and is operated to a mid position when the switch is in any position intermediate its normal and reverse positions. In the normal position of controller J, contacts 3—3a, 5—5a and 6—6a are closed, in the reverse position of controller J contacts 1—1b, 2—2b and 4—4a are closed, and in the mid position of controller J contacts 1—1a, 2—2a, 3—3a, 4—4a, 5—5b and 6—6b are closed.

The reference character K designates a circuit controller comprising two movable contact fin-

gers 7 and 8 which are operatively connected with switch mechanism SM, the arrangement being such that contact fingers 7 and 8 are operated to a normal position, that is, the position illustrated in the drawing, closing contacts 7—9 and 8—10 when mechanism SM is conditioned to actuate switch S to its normal position, and contact fingers 7 and 8 are operated to a reverse position closing contacts 7—11 and 8—12 when mechanism SM is conditioned to actuate switch S to its reverse position.

Switch mechanism SM is controlled in part by a manually operable control element, such as lever E, which may, for example, be a switch lever of an interlocking machine. Lever E usually will be located at a point remote from the switch, and is adapted to assume various positions, as illustrated in the diagram immediately below the lever in the drawing. These positions are full normal position N, normal indication position B, reverse indication position D, full reverse position R, and intermediate positions X and Y. Lever E is provided with a plurality of contacts designated by the reference characters 13 to 20 inclusive, so arranged as to be closed at different positions of the lever. The positions in which the contacts are closed are shown in the drawing by the reference characters designating the positions of lever E. For instance, contact 20 of lever E bears the reference character RD, which means that contact 20 is closed when the lever is in its full reverse position R, its reverse indication position D, or any position between the two.

Lever E is provided with suitable means for indicating at the lever the position of switch S. As here shown, the indication means comprise magnets 21 and 22 controlling locking dogs 21a and 22a, respectively, and which locking dogs 21a and 22a engage associated lever segments 21b and 22b, respectively. Segments 21b and 22b are operably connected with lever E. It is to be understood that when magnet 21 is energized, locking dog 21a is actuated out of engagement with segment 21b, and when magnet 22 is energized, locking dog 22a is actuated out of engagement with segment 22b. It should be pointed out that when lever E is in its normal position N, the energization of magnet 21 permits lever E to be moved toward its reverse position R, and with lever E at its normal indication position B the energization of magnet 21 permits lever E to be moved to its normal position N. In like manner, with lever E in its reverse position R, the energization of magnet 22 permits lever E to be

moved toward its normal position N, and with lever E in its reverse indication position D the energization of magnet 22 permits lever E to be moved to its reverse position R.

5 The reference character WP designates a polarized indication relay which is controlled jointly by circuit controller K and circuit controller J, and which functions to govern the indication means for lever E, and as a second control element for mechanism SM. Relay WP, in accordance with usual practice, is preferably located adjacent lever E.

Having thus described the various parts of the apparatus of Fig. 1 embodying my invention, I 15 shall now explain their operation.

I shall first assume that lever E, switch S, and circuit controllers J and K are in their respective normal positions, that is, the positions shown in Fig. 1. In this condition of the apparatus, 20 relay WP is energized by virtue of a normal circuit passing from terminal B of a suitable source of current, such as a battery not shown, through contact 9-7 of controller K, contact 5a-5 of controller J, winding of relay WP, and contact 25 6-6a of controller J to terminal C of the source of current. Relay WP is thus energized by current of a polarity which I shall term normal polarity, closing its front contact 23 and operating its polar contact members 24 and 25 to the left- 30 hand position, as viewed in Fig. 1, to make contact with normal polar contacts 26 and 27 respectively. Also in this normal condition valve magnets NV and RV are deenergized.

I shall now assume that it is desired to move 35 switch S to its reverse position. To do this, a latch contact 28 of lever E is first closed so that a circuit passing from terminal B over the detector and route locking circuits, which are indicated conventionally on the drawing since the 40 form of these circuits forms no part of my present invention, through latch contact 28 of lever E, contact 14 of lever E and the winding of magnet 21 to terminal C is completed. Magnet 21 becomes energized to lift its locking dog 21a and 45 lever E may be moved away from its normal position. When lever E is thus released by the energization of magnet 21, the operator is assured that the detector and route locking circuits are clear.

50 The lever E is next moved to its reverse indication position D, where further movement is prevented by locking dog 22a of magnet 22 engaging segment 22b of lever E. At this position of lever E, however, a first energizing circuit for valve magnet RV is completed. This circuit passes from terminal B through front contact 23 of relay WP, wire 29, lever contact 18, wire 30, normal polar contact 25-27 of relay WP, control wire 31, the winding of magnet RV, wire 32, 55 and lever contact 20 to terminal C; and valve magnet RV becomes energized. Switch mechanism SM now operates to move switch S to its reverse position, controller K being first actuated to its reverse position to open contacts 7-9 and 8-10 and to close contacts 7-11 and 8-12. 60 The opening of contact 7-9 opens the previously traced normal circuit for relay WP, and relay WP is deenergized and releases, opening front contact 23 to open the previously traced first circuit for magnet RV. Magnet RV is, however, retained energized by virtue of a second energizing circuit passing from terminal B through back contact 33 of relay WP, control wire 31, the winding of magnet RV, wire 32, and lever contact 75 20 to terminal C. During the movement of the

switch, controller J is actuated to its mid position so that contacts 1-1a, 2-2a, 3-3a, 4-4a, 5-5b and 6-6b are closed. Relay WP is now provided with two short circuit paths across its winding, one path including contacts 1-1a and 2-2a of controller J, and the other path including contacts 5-5b and 6-6b of controller J. With controller J in its mid position, a third energizing circuit for valve magnet RV is provided, the circuit passing from terminal B through contact 4a-4 of controller J, contact 3-3a of controller J, wires 34 and 31, the winding of magnet RV, wire 32 and lever contact 20 to terminal C.

When switch S reaches its full reverse position, 15 circuit controller J also is in its reverse position where contacts 1-1b, 2-2b and 4-4a of circuit controller J are closed. The opening of contact 3-3a of circuit controller J opens the previously traced third circuit for valve magnet RV, and the opening of contacts 1-1a, 2-2a, 5-5b and 6-6b of controller J removes the short circuit paths across the winding of relay WP. A reverse circuit passing from terminal B through contact 2b-2 of circuit controller J, the winding of relay WP, contact 1-1b of circuit controller J, and contact 8-12 of controller K to terminal C is now completed; and relay WP is supplied with current of a polarity which I shall term reverse polarity. Relay WP is now energized to open back contact 33, to close front contact 23, and to shift its polar contact members 24 and 25 to the right-hand position to make engagement with reverse polar contacts 35 and 36, respectively. The opening of back contact 35 33 opens the second energizing circuit for valve magnet RV, and the opening of normal polar contact 25-27 opens the first energizing circuit of magnet RV, so that valve magnet RV becomes deenergized, switch mechanism SM now being at 40 its reverse position. The closing of reverse polar contact 25-36 of relay WP completes a circuit passing from terminal B through front contact 23 of relay WP, wire 29, lever contact 18, wire 30, reverse polar contact 25-36, wire 31, lever contact 16, and the winding of magnet 22 to terminal C; and magnet 22 is energized to lift its locking dog 22a out of engagement with segment 22b of lever E, thereby releasing lever E and indicating that switch S has been moved to 45 its reverse position. Lever E may now be moved to its reverse position R.

When the switch has been moved to its reverse position in the manner just described and it is desired to restore it to its normal position, latch contact 28 of lever E is first closed to complete a circuit which may be traced from terminal B over the detector and route locking circuits, through latch contact 28, lever contact 13, and the winding of magnet 22 to terminal C; and magnet 22 becomes energized to lift locking dog 22a so that lever E may be moved to its normal indication position B, where further movement of the lever is prevented by locking dog 21a of magnet 21 engaging segment 21b of lever E. At 55 this position of the lever, a first energizing circuit for valve magnet NV is completed, the circuit passing from terminal B through front contact 23 of relay WP, wire 29, lever contact 17, wire 38, reverse polar contact 24-35 of relay WP, control wire 31, the winding of valve magnet NV, wire 40, and lever contact 19 to terminal C; and valve magnet NV becomes energized so that mechanism SM operates switch S to its normal position. The mechanism SM first operates controller K to its normal position so that 60 65 70 75 80 85 90 95

contacts 7-11 and 8-12 of controller K are opened and contacts 7-9 and 8-10 are closed. The opening of contact 8-12 opens the previously traced reverse circuit for relay WP, so that relay WP is deenergized and releases to open front contact 23 interposed in the previously traced first circuit for valve magnet NV. Magnet NV is, however, retained energized by virtue of a second energizing circuit passing from terminal B through back contact 33 of relay WP, control wire 31, the winding of valve magnet NV, wire 40, and lever contact 19 to terminal C. The mechanism SM also operates controller J first to its mid position where the winding of relay WP is provided with the two short circuit paths as previously mentioned, and valve magnet NV is provided with a third energizing circuit which may be traced from terminal B through contact 4a-4 of controller J, contact 3-3a of controller J, wires 34 and 31, the winding of valve magnet NV, wire 40, and lever contact 19 to terminal C.

When switch S reaches its normal position, controller J is also operated to its normal position, so that the short circuit paths across the winding of relay WP are now removed, and the third circuit for valve magnet NV is opened. The previously traced normal circuit for relay WP is now completed, and relay WP becomes energized to open back contact 33, to close front contact 23, and to operate its polar contact members 24 and 25 to the left-hand position to close normal polar contacts 24-26 and 25-27. The opening of back contact 33 of relay WP opens the second energizing circuit of magnet NV, and the opening of reverse polar contact 24-35 of relay WP opens the first energizing circuit of magnet NV with the result that magnet NV is deenergized subsequent to the movement of switch S to its normal position. With the energizing of relay WP by current of normal polarity, a circuit passing from terminal B through front contact 23 of relay WP, wire 29, lever contact 17, wire 38, normal polar contact 24-26 of relay WP, wire 39, lever contact 15, and the winding of magnet 21 to terminal C is completed, and magnet 21 becomes energized to lift its locking dog 21a out of engagement with segment 21b, thereby releasing lever E and indicating that switch S is restored to its normal position. Lever E may now be moved to its normal position N.

It should be pointed out that relay WP functions as one control element of valve magnets NV and RV as well as controlling the indication means for lever E. It should be noted that control wire 31 is connected with both magnets NV and RV, is connected with both normal polar contact 25-27 and reverse polar contact 24-35 of relay WP and is common to the energizing circuits of both magnets NV and RV. Furthermore, it should be pointed out that apparatus embodying my invention provides means for selectively controlling magnets NV and RV solely by virtue of contacts of lever E and relay WP and other circuit selecting devices such as asymmetric units are not required.

In Fig. 2, the apparatus is the same as that shown in Fig. 1 except that circuit controller J functions as a control element for mechanism SM in place of the relay WP, and bus wires 41 and 42, which are connected respectively with terminal B and terminal C of the source of current, extend between the lever location and the switch.

The operation of the indication means for lever E in Fig. 2 is similar to that previously described

in connection with Fig. 1, and it is believed, therefore, that this latter operation will be apparent from the foregoing description of Fig. 1 and from an inspection of Fig. 2 without further detailed description.

In the normal position of the apparatus, as shown in Fig. 2, lever E, switch S, switch mechanism SM, circuit controller J and circuit controller K are all in their respective normal positions, and valve magnets RV and NV are deenergized.

When it is desired to move switch S to its reverse position, lever E is moved to its reverse indication position D. At this position of the lever, an energizing circuit passing from terminal B through bus wire 41, wire 43, contact 3a-3 of circuit controller J, wire 44, the winding of valve magnet RV, control wire 45, contact 20 of lever E, wire 41 and bus wire 42 to terminal C is completed to energize magnet RV so that mechanism SM is actuated to move switch S to its reverse position.

When the switch reaches its full reverse position, circuit controller J is operated to its reverse position so that contact 3-3a of controller J is open to open the previously traced circuit for valve magnet RV, and contact 4-4a of circuit controller J is closed to prepare an energizing circuit for magnet NV. With the relay WP energized by current of reverse polarity in the manner explained in Fig. 1, lever E may be moved to its reverse position R and the apparatus is in its reverse position.

When it is desired to restore the switch to its normal position, lever E is moved to its normal indication position B. At this position of lever E, an energizing circuit is completed from terminal B through bus wire 41, wire 43, contact 19 of lever E, control wire 45, the winding of magnet NV, wire 50, contact 4-4a of circuit controller J, wire 51 and bus wire 42 to terminal C so that magnet NV becomes energized, and mechanism SM actuates switch S to its normal position. When switch S reaches its normal position, circuit controller J is operated to its normal position so that contact 4-4a of circuit controller J is opened to open the energizing circuit for magnet NV, and contact 3-3a is closed to prepare the circuit for magnet RV. The relay WP is now energized by current of normal polarity in the manner previously pointed out, and lever E may be moved to its normal position.

It should be noted that control wire 45 is connected with both magnets NV and RV, is connected with both contacts 19 and 20 of lever E, and is common to the energizing circuits of both magnets NV and RV. Furthermore, it should be noted that the apparatus of Fig. 2 provides means for selectively controlling the magnets NV and RV solely by virtue of the contacts of lever E and controller J and other circuit selecting devices are not required. It follows that since no asymmetric units are required for selectively controlling the magnets NV and RV, the bus wires located at each control point may be connected with the sets of normal contacts and with the sets of reverse contacts of the control elements in a selected manner so that no improper or inoperative condition of the apparatus dependent upon the polarity of the control current may arise.

One advantage of my invention is the provision of novel and improved apparatus for controlling a power operated switch from a remote point with the minimum number of control wires between such point and the switch. A further ad-

vantage of my invention is the provision of means, in apparatus of the type described, for selectively controlling the switch by means of simple and economical apparatus.

5 Although I have herein shown and described only two forms of apparatus embodying my invention, it is understood that various changes and modifications may be made therein within the scope of the appended claims without departing from the spirit and scope of my invention.

10 Having thus described my invention, what I claim is:

15 1. In combination, a railway switch having a normal and a reverse position, a switch operating mechanism operatively connected with said switch, said switch mechanism being provided with a normal magnet and a reverse magnet and being effective for moving said switch to its normal or its reverse position according as said 20 normal or said reverse magnet is energized, a polarized relay, means governed by the switch for supplying said relay with current of normal or reverse polarity according as said switch is in its normal or its reverse position, a manually 25 operable lever having a normal and a reverse position and provided with a normal and a reverse contact, a single control wire extending from a normal and a reverse polar contact of said relay to both of said magnets; a first circuit 30 for energizing said normal magnet including said normal position lever contact, said control wire, and a front contact and said reverse polar contact of said relay; a second circuit for energizing said normal magnet including said normal position lever contact, said control wire, and a back 35 contact of said relay; a first circuit for energizing said reverse magnet including said reverse

position lever contact, said control wire, and a front contact and said normal polar contact of said relay; and a second circuit for energizing said reverse magnet including said reverse position lever contact, said control wire, and a back 5 contact of said relay.

2. In combination, a railway switch having a normal and a reverse position, a mechanism having a normal magnet and a reverse magnet and operatively connected with the switch for moving said switch to its normal or its reverse position according as said normal or said reverse magnet is energized, said mechanism being provided with a first contact closed in all positions of said switch except its normal position and a second contact closed in all positions of said switch except its reverse position, a polarized relay, means governed by the switch for energizing said relay with current of normal or reverse polarity according as said switch is in its normal or its reverse position, a manually operable lever having a normal and a reverse position and provided with a normal and a reverse contact, a control wire, a first circuit for said normal magnet including said normal lever contact, said control wire, and said reverse polar contact of said relay; a second circuit for said normal magnet including said normal lever contact and said first and second contacts of said mechanism in series; a first circuit for said reverse magnet including said reverse lever contact, said control wire, and said normal polar contact of said relay; and a second circuit for said reverse magnet including said reverse lever contact and said first and second mechanism contacts in series.

JOHN W. LOGAN, JR.
